UNITED STATES PATENT OFFICE.

FELIX ORDAKOWSKI, OF CLARKSBURG, WEST VIRGINIA.

WINDOW AND SCREEN.

1,262,552.

Specification of Letters Patent.

Patented Apr. 9, 1918.

Application filed September 8, 1917. Serial No. 190,839.

To all whom it may concern:

Be it known that I, FELIX ORDAKOWSKI, a citizen of Russia, residing at Clarksburg, in the county of Harrison and State of West Virginia, have invented certain new and useful Improvements in Windows and Screens, of which the following is a specification.

This invention relates to windows and screens therefor and has special reference to 10 a detachable roller window screen.

One important object of the invention is to improve and simplify the general construction of devices of this character.

A second important object of the invention 15 is to provide an improved roller screen which may be attached to any window now in existence without interfering with the usual movement of such window to any extent and without making it necessary to reconstruct any of the parts of the window 20 or frame.

A third important object of the invention 25 is to provide a screen of this character which may be locked in closed position both for convenience in portability and to hold the window locked.

With the above and other objects in view, 30 as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a face view of the inside of the lower portion of a window equipped with this invention.

40 Fig. 2 is a section on the line 2—2 of Fig. 1.

Fig. 3 is a section on the line 3—3 of Fig. 2.

Fig. 4 is an enlarged detail plan view of 45 the casing removed from the window and broken away in order to permit the device being shown on a large scale.

Fig. 5 is a section on the line 5—5 of Fig. 4.

50 Fig. 6 is a perspective view of the locking bolt used herewith.

In the embodiment of the invention herein disclosed there has been disclosed a window and its frame, the frame consisting of side members 10 and a sill 11 and the window

having ordinary glazed sash 12. Movable into and out of position on the sill 11 is a casing 13, the window molding being cut away at its lower part to accommodate the ends of the casing as can be seen by reference to Fig. 1 at 14. Within this casing is mounted an ordinary spring shade roller 15 whereon is wound a flexible screen 16 fitting between the sides. On the free edge of this screen there is provided a bar 17 having lugs or studs 18 on its upper edge which are arranged to fit in suitable openings 19 on a bar 20 screwed or otherwise secured to the lower edge of the sash 12. Thus the screen is readily detachable from the sash and the sash can be shut down in the ordinary manner, a pocket 21 being provided in the sill for the reception of the studs 18. The casing is preferably made with the front and top hinged as at 22 to the bottom and these parts 20 are held in locked position by means of hooks 23. Furthermore, within the casing is a cam plate 24 fixed to the top and through the casing passes a locking bar 25 having a bent portion 26 forming a lug which engages the cam bar when in one position to force the locking bar inward while, when the locking bar is in its second position, the lug is so moved as to permit outward movement of the locking bar as a whole. On the end of this locking bar is a lug 27 which is arranged to fit, when the window is closed, in an opening 28 formed in the bar 17. Thus when the window is closed it can be locked in closed position by the locking bar and 90 also, when it is desired to remove the screen entirely from the window, the edge of the screen may be locked in position so that it cannot slip into the casing and wind up too far on the roller. It will be obvious that by 95 means of this construction the casing can be put in place or taken out at will, and the screen can be connected or disconnected from the window sash. In order to hold the casing in place a thumb latch 28 is preferably 100 provided.

There has thus been provided a simple and efficient device of the kind described and for the purpose specified.

It is obvious that many minor changes 105 may be made in the form and construction of the invention without departing from the material principles thereof. It is not therefore desired to confine the invention to the exact form herein shown and described but 110

it is wished to include all such as properly come within the scope claimed.

Having thus described the invention, what is claimed as new, is:—

- 5 1. The combination with a window frame and sash; of a casing removably fixed in the lower part of said frame, a roller in said casing, a screen carried by said roller, coacting connecting means on the sash and the end of
- 10 the screen, and locking means carried by the casing and engageable with the connecting means on the screen to prevent movement of the latter relative to the casing.
- 15 2. The combination with a window frame and sash; of a casing removably fixed in the lower part of said frame, a roller in said casing, a screen carried by said roller, coacting connecting means on the sash and the end of the screen, comprising bars fixed to the
- 20 lower edge of the sash and the end of the screen, one of said bars having openings

therein and the remaining bar carrying studs engageable in said openings.

3. The combination with a window frame and sash; of a casing removably fixed in 25 the lower part of said frame, a roller in said casing, a screen carried by said roller, coacting connecting means on the sash and the end of the screen, and locking means carried by the casing and engageable with 30 the connecting means on the screen to prevent movement of the latter relative to the casing, the means on the screen also having a lock bolt receiving opening, and a lock bolt carried by the casing and arranged to 35 enter the last-mentioned opening.

In testimony whereof I affix my signature.

FELIX ORDAKOWSKI.
